UNITED STATES PATENT OFFICE.

LEVI M. BOWMAN, OF FORT WORTH, TEXAS, ASSIGNOR TO WILLIAM C. FARMER, OF TULSA, OKLAHOMA.

RAZOR-STROPPING DEVICE.

1,150,658.

Specification of Letters Patent.

Patented Aug. 17, 1915.

Application filed August 26, 1913. Serial No. 786,794.

To all whom it may concern:

Be it known that I, LEVI M. BOWMAN, a citizen of the United States, residing at Fort Worth, in the county of Tarrant and State of Texas, have invented certain new and useful Improvements in Razor-Stropping Devices; and I do hereby declare the following to be a full, clear, and exact description of the invention, such as will enable others skilled in the art to which it appertains to make and use the same.

This invention relates to new and useful improvements in razor stropping devices and has for its object the provision of a device of the above character which will efficiently strop a razor blade.

Another object of my invention is the provision of such a device which will permit an inexperienced person to strop a blade as satisfactorily as could be done by one practised in the art.

A still further object of my invention is the provision of such a device which will eliminate any possibility of cutting the strop, the danger of which is always present when it is being done without the use of my improved device.

Still another object of my invention is the provision of such a device which will be cheap in construction and simple in operation and the amount of mechanism used will be materially decreased.

With the above and other objects in view I now proceed to describe my invention in the following specification and accompanying drawings, in which,

Figure 1 is a longitudinal sectional view of my improved razor stropping device. Fig. 2 is a transverse sectional view taken on line 2—2 of Fig. 1, and Fig. 3 is a transverse sectional view on the line 3—3 of Fig. 1.

Referring to the drawings by characters of reference, the numeral 1 indicates the handle of the improved stropping device having secured at one end thereof the ferrule 2 formed with an inwardly directed flange 5^a having a slot or recess 5^b therein. A bearing member 5 is secured to the ferrule 2 interiorly of the flange 5^a and is formed with a central opening and a peripheral recess. A pin or stub shaft 3 is formed integral with the bearing member 5, projects radially within the peripheral recess and a pinion 4 is rotatably mounted thereon. An elongated bearing member 8 is non-rotatably secured

in the central opening of the bearing member 5 and rotatably receives the shaft 6 to the inner end of which is secured a crown gear 7 meshing with the pinion. A right angularly directed member 10 is secured to the shaft 6 at its outer extremity and carries the guide 11 into which the blade holder 12 is adapted to pass. This guide 11 is preferably formed as clearly illustrated in Fig. 2 and is extended rearwardly as shown in Fig. 1 to 60 overlie the razor strop when the device is in use. A sleeve 13 is rotatably mounted over the bearing member 8 and is retained in spaced relation to the latter by spacing elements 9 and 14 and has formed integrally at 65 its inner extremity suitable gear teeth which mesh with the teeth of the pinion 4, which project through the recess 4 and thereby transmit power to the same. A second ferrule 15 is telescopically engaged over the ferrule 2 and is provided with an inwardly directed flange overlying the flange 5. 70

It will be clearly seen from the foregoing that when it is desired to make use of my improved stropping device the blade of the 75 razor, which is to be sharpened is placed in the blade holder 12 and the device placed on the razor strop in the usual way with the sleeve on roller 13 in frictional engagement with the stropping device. It will be obvious that owing to the rolling action of the roller 13 it will cause the pinion 4 to revolve, thereby transmitting power to the gear wheel 7 which in turn will cause the shaft 6 to rotate inside of the bearing 8 in a direction opposite to the direction of travel of the roller, until the blade holder is swung downwardly and into frictional engagement with the stropping surface which will cause the edge of the blade to be drawn thereacross. 80 Upon reversing the direction of travel it will be apparent that the roller 13 will again revolve and cause the blade to swing over and frictionally engage the strop on its opposite side, thus sharpening both sides of the blade 85 and assuring a perfect edge. 90

While in the foregoing I have shown and described the preferred embodiment of my invention, I wish it to be understood that I may change the specific arrangement and combination of parts without in any way departing from the spirit and scope of my invention, as defined in the appended claim. 100

What is claimed is:

A device of the character described com. 110

prising a handle, a ferrule secured to the end of said handle having an inwardly directed flange formed with a recess, an apertured bearing member secured in said ferrule inwardly of said flange and having a peripheral recess, a stub shaft formed integral with said bearing member disposed centrally within said peripheral recess, a pinion rotatably mounted on said stub shaft, a tubular bearing member non-rotatably secured in the first mentioned bearing member and extending exteriorly of said ferrule, a shaft rotatably mounted in the second bearing member and projecting outwardly of the opposite ends of the latter, a crown gear on the inner extremity of said shaft meshing with

said pinion, a pair of spacing elements secured on said tubular bearing member, a sleeve rotatably mounted on said spacing members, and having teeth formed at its inner extremity meshing with said pinion, an angular extension at the outer extremity of said shaft, a blade holding device secured to said angular extension and extending inwardly in parallel relation to said shaft. 20 25

In testimony whereof I affix my signature in presence of two witnesses.

LEVI M. BOWMAN.
